UNITED STATES PATENT OFFICE.

GUNTHER P. G. SCHMIDT, OF MILWAUKEE, WISCONSIN.

SATURATOR.

Application filed July 22, 1921. Serial No. 486,909.

This invention relates to saturators, and is particularly directed to an automatic device.

Objects of this invention are to provide a saturator in which liquid, added to replace the used saturated liquid, is first mixed with the previously cooled liquid and thereafter intimately mixed with the gas and storage liquid before it may be finally withdrawn from the apparatus so that it is impossible to withdraw liquid that has not been properly cooled and saturated; and to provide a device of this type which will automatically carry on its various functions independently of any attention upon the part of the operator.

Further objects are to provide a saturating apparatus in which the saturating process is repeated throughout a great number of cycles before the liquid is finally withdrawn from the apparatus; to provide such an apparatus in which both the infusion or injection and the drip or free absorption of gas may be simultaneously provided; in which the liquid in its passage through the apparatus is effectively cooled and allowed to absorb increased quantities of the gas; in which means are provided for automatically regulating the quantity of liquid delivered to the apparatus in proportion to the demands made upon such apparatus for the completely saturated liquid; and to provide an apparatus in which absorption is carried on while the liquid being treated is distributed in a thin film, and is in intimate contact with tempering means.

Further objects are to provide a saturator in which provision is made whereby the operator at all times may inspect the apparatus and be assured of the proper functioning thereof; in which the air which normally accumulates adjacent the upper portion of these devices may be utilized and withdrawn from the apparatus to operate portions of the mechanism; and to provide such a device in which the circulating liquid is caused to intimately contact in a very thin film with cooling coils.

Embodiments of the invention are shown in the accompanying drawings, in which:

Fig. 1 is a partial sectional elevation of the complete apparatus.

Fig. 2 is a detail sectional view of the upper portion of the carbonator.

Fig. 3 is a detail partly in section of the control valve for the clutch.

Fig. 4 is a plan view of the gearing, clutch and driving motor.

Fig. 5 is a sectional view showing the clutch in detail.

Fig. 6 is a fragmentary sectional view showing a modified form of the invention.

The apparatus comprises a tank 1 which is provided with dome-shaped top and bottom portions 2 and 3 joined by a tie rod 4. This tank is completely covered with heat insulating material 5. From the bottom of the tank, a pipe 6 extends and is joined to a fitting 7 which serves as a coupling for the circulatory and service pipes hereinafter described. This coupling may be provided with a drain valve as indicated in Fig. 1. From the coupling 7 a pipe 8 extends to a continuously driven centrifugal pump 9. The pump 9 forces the water withdrawn from the bottom of the tank upwardly through a pipe 10, a mixing chamber or sight glass 11 and into the upper portion of the container or tank 1 through a pipe 12. The pipe 12 is provided with branches or arms 13 which in turn are provided with two series of nozzles 14 and 15 arranged at different distances from the central portion of the tank. These nozzles discharge the water into a drip pan 16, which, as may be seen from Fig. 2, is provided with an inner and outer annular channel 17 and 18. This drip pan is provided with a series of serrations 19 adjacent its upper inner and outer edges for subdividing the water, the contained gas tending to atomize it into small streams and is similarly provided adjacent its inner and outer bottom edges with corresponding serrations 20 for further subdividing the water into small streams or drops. These bottom inner and outer serrations are in line with two sets of cooling coils 21 and 22, respectively, the smaller coil being positioned within the larger one. The streams or drops of water from the serrations 20 fall upon these coils and tend to follow them both vertically and in the direction of their downward inclination, the water being thus distributed upon the coils in a thin film.

Water dripping from one turn of either coil will, of course, pass to the next and be distributed thereon. The tendency of the water to distribute in a film upon the coils delays the downward movement, and also provides maximum exposure for gas absorption. These cooling coils are provided with inlet pipes 23 and 24 and outlet pipes 25 and 26.

respectively so that a refrigerant may be continuously passed through these cooling coils. The normal water level in the tank is indicated at 27.

- 5 The carbon dioxide is supplied from a suitable source such as indicated at 28 and passes through a control valve 29 and outwardly through a nozzle 30 positioned with in the fitting 31 which latter joins the pipe 10 and the sight glass 11. This arrangement allows the incoming carbon dioxide to be injected into the flowing liquid and the operator may watch this process through the sight glass 11. The water and the carbon dioxide which is partly absorbed thereby, together with the uncombined carbon dioxide, passes upwardly through the pipe 12 and into the drip pan. From this point, the gas that has not been absorbed passes 15 into the tank 1 and the water is finely divided and cooled and subjected, in its finely divided state, to the action of this gas to thereby absorb additional quantities of the gas, due both to its large surface exposure 20 to the gas and to its lower temperatures. The carbonated water may be withdrawn from the apparatus through the pipe 32 which obviously may be provided with a cut off valve 33 if it is desired. A thermometer 34 may be inserted within the pipe 8 and accurately gives the temperature of the carbonated water inasmuch as it is continuously subjected to such flowing stream. The height of the liquid within the tank 35 may be indicated by means of a water level glass 35 connected at its lower end to a pipe 36, which in turn joins the fitting 7, and at its upper end to a pipe 38 which passes into the tank 1.
- 40 Referring to Fig. 4 it will be seen that an electric or other suitable motor 39 has a direct connection by means of its shaft 40 with the impeller of the rotary pump 9. The same motor may be utilized to drive 45 the pump 43 through a pinion 41, gear wheel 42, friction clutch 43' (see also Fig. 5), shaft 46, pinion 47, gear wheel 48, crank 49, and connecting rod 51, the latter being pivoted to the piston rod 50 as best shown 50 in Fig. 1.
- The gear wheel 42 is loose on the shaft 46 and preferably integrally connected with the outer member or housing of the friction clutch 43'. This clutch is illustrated in Fig. 55 5 as a clutch of the multiple disk type, the alternate disks 44 being in sliding-key connection with the outer member or housing and the intermediate disks having similar sliding-key connection with a sleeve 45 fast 60 on the shaft 46, whereby when the disks are pressed together, as herein explained, motion will be transmitted from the gear wheel 42 to the shaft 46. The pinion 47 is fast on the shaft 46.
- 65 The friction disks of the clutch 43' are

normally separated or relieved from pressure upon each other. The pump 43 serves as a feed pump, whereby water is supplied to the system. This pump should, therefore, be operated intermittently, whereas the rotary pump 9, should be operated continuously to circulate the liquid and maintain continuous delivery from the drip pans downwardly over the refrigerating coils. The friction clutch 43' will, therefore, have 70 its disks normally separated or relieved from pressure, whereby the motor may operate continuously to drive the pump 9 without transmitting motion to the pump 43, except during periods when the clutch 80 is set for motion transmission.

Automatic means are provided for pressing the clutch disks together and transmitting motion to the feed pump 43 whenever the quantity of liquid in the tank 1 falls 85 below a predetermined level. The pressure may be conveniently supplied from the gas in tank 1, the delivery of the gas to the clutch being controlled by a float actuated valve mechanism contained within the cas- 90 ing 52 (Fig. 1 and Fig. 3).

It is desirable that the means for operating the valve mechanism in the casing 52 be accessible at all times. Therefore, instead of employing ordinary float mechanism within the tank 1 to control the level of the liquid therein through said valve mechanism, I utilize for this purpose an exterior regulator or counterbalanced tank 53 which is supported from a scale beam 58 in 100 a position with its middle portion at a level corresponding with the desired level of the liquid in the tank 1. The tank 53 is provided at its bottom and top, respectively, with flexible ducts 54 and 55. The duct 54 105 is connected with the pipe 36 through the pipes 56, and the duct 55 is connected with the pipe 38 through the pipe section 57. The flexible ducts or hose pipes 54 and 55 allow substantially free upward and downward 110 movement of the tank 53 in correspondence with its decreasing or increasing weight, i. e., the weight of the tank and its contents.

The scale beam 58 is fulcrumed at 59 and provided with a counterweight 60. The fulcrum 59 is vertically adjustable, being mounted upon a slide 61 movable along a standard 62 and provided with a slot 61', whereby it may be secured in any desired position of adjustment by a set screw 61''. This adjustment is desirable not only to facilitate setting the tank 53 at the proper level in the first instance, but to also permit of readjustments under varying conditions of the liquids and gases to be treated. 120

The valve chamber 52 is mounted upon the slide 61. Gas under pressure may be delivered to the housing of the clutch 43' from the tank 1 through the pipes 64, 65, 66, flexible hose or duct 67, valve chamber 130

52, flexible hose 68, and pipe or duct 69, which leads through the outer or end wall of the clutch housing to the diaphragm chamber 69'. This gas pressure is exerted 5 within the chamber 69' upon the diaphragm 63 to bring the clutch disks together and when this pressure is relieved the disks are allowed to separate, the diaphragm being automatically retracted by a spring 89, 10 (Fig. 5). A coupling 70 facilitates disconnecting pipe 69 when the diaphragm is to be replaced. A cut-off valve may be employed at 71 and, if desired, an ordinary blow-off valve 72 and pressure indicator 73 15 may be provided at the upper end of the pipe 64, whereby the pressure within tank 1 may be ascertained and excess pressures relieved. The valve mechanism disclosed in Fig. 3 not only allows a delivery of gas 20 from tank 1 to actuate the clutch diaphragm, but also provides for the release of the clutch by cutting off the further supply of gas from tank 1 and allowing the gas in the diaphragm chamber 69' of the clutch, 25 and in the pipe connections, to escape to the open air when the liquid in the float or controlling valve 53 exceeds a predetermined weight.

When the liquid in the controlling tank 30 53 falls below the predetermined weight (i. e., the desired level in tank 1), the counterbalance 60 tilts the scale beam 58 to lift the controlling tank 53 and simultaneously press downwardly upon the valve stem 74, 35 thereby admitting gas to the diaphragm chamber of the clutch as above explained. The plunger 74 extends into the valve casing 52 to actuate the piston and valve therein. This plunger is pressed upwardly by 40 means of a spring 75 having its upper end seated against an annular collar or flange connected with the valve stem and is provided at its lower end with a needle valve point 76. This needle valve point cooperates with a corresponding seat 77 formed within the port 85 of a ported guide piston 78. The piston valve 78 is connected by a rod 79 with a check valve 80, which closes 45 upon a valve seat 81 to prevent the passage of gas or air from the chamber 82 to the chamber 83 of the valve casing and thereby prevent the passage of gas from the tubing or pipe 67 to the pipe or tubing 68. It is to be noted that in the normal position of 50 this valve 80 as shown in Fig. 3 that the valve 80 is held seated both by the pressure of the gas or air and by the spring 84 so that air under pressure will not be transmitted to the diaphragm 63 of the clutch. It 55 will also be noted that the pipe 68 is placed in communication with the exterior air by means of the duct 85 extending upwardly through the piston 78 and into the upper end of which duct the needle valve seats. 60 When the plunger 74 is moved downwardly

65 by the lever 58, the first step in the operation of the valve is the seating of the valve 76 upon its seat 78, thereby cutting off the communication of the diaphragm chamber 70 of the clutch with the exterior air. Further motion of the plunger 74 unseats the valve 75 75 and allows air (gas or mixed gas and air) under pressure to pass from the pipe 67 to the pipe 68 and thence to the diaphragm 63.

While I have illustrated insulating covering only upon the tank 1, it is to be understood that it is not essential to my invention to what extent the insulating covering is used for any portion of the system, the 80 use of insulating coverings to prevent the transfer of heat through the walls of chambers and pipes being well understood.

The operation of the entire apparatus is as follows: When the valve 29 controlling the 85 carbon dioxide is open, such gas passes upwardly into the sight chamber or mixing chamber 11 and into the water, the circulating rotary pump 9 being in continuous operation. This partly charged water together with free gas passes into the tank 1 and further mixing occurs in such tank as previously described. If, for example, carbonated water is withdrawn through the pipe 32 only the thoroughly carbonated cool 90 water will pass outwardly from the apparatus as the incoming water furnished by the pump 43, if such pump is in operation, is passed first into the inlet pipe 8 of the rotary pump, suitable check valves 86 and 87 95 and a controlling valve 88 being provided within this supply pipe. When the water level falls below a predetermined point, the counterweight 60 overcomes the weight of the tank 53 and the water carried therein, 100 and moves the plunger 74 of the valve 52 downwardly, thereby supplying compressed gas from tank 1 to the diaphragm 63 and closing the clutch, that is to say, forcing the friction disks against each other. This 105 causes the feed pump 43 to operate and such operation of the pump continues until the desired water level has again been secured. At this time, the weight of the water within the tank 53 overcomes the counterweight and 110 places the diaphragm 63 in communication with the external air. It is to be noted that to guard against sticking of the disks due to defective operation of the diaphragm, a spring 89 is provided which is socketed within the shaft 46 and bears outwardly against the diaphragm, thereby insuring the release of the friction disks. If desired, a sampling spigot 90 may be provided at any suitable 115 part of the apparatus, conveniently communicating with the pipe 56.

Great importance is attached to the provision of means for injecting gas into the water which is being supplied to the drip pans 16 and to the connection of the feed 120 125 pipe 17.

pump 43 for delivering to the ascending column of water in the pipes 8 and 10. It will be obvious that water delivered into the system by the feed pump 43 will be drawn 5 upwardly in the pipe 8 by the pump 9 and delivered into the tank 1, through the pipe 10, mixing chamber 11 and pipe 12. Therefore, the uncharged feed water will receive an initial charge in the mixing chamber 11 10 before it enters the tank 1 and will be sufficiently charged so that it will not very materially dilute the liquid contents of tank 1. It will be understood that by discharging gas through the nozzle 30, upwardly into the 15 mixing chamber 11, the gas will tend to cause a violent ebullition of water and will be thoroughly distributed through the water into the mixing chamber. It is possible by this means to charge the water to a point 20 approaching saturation at the temperature prevailing in said chamber. But I have found that complete saturation and particularly complete saturation at low temperatures cannot be attained in this manner and 25 can only be quickly and economically attained by combining this water charging means in the mixing chamber 11 with the co-operating water charging means and temperature reducing agencies contained within 30 tank 1.

I have further found by combining the gas charging means associated with the mixing chamber with the co-operating means within the tank 1 it is possible to maintain 35 a supply of substantially uniformly charged liquid in the tank 1 which closely approximates saturation at low temperatures.

In certain cases, it may not be necessary to have the supply pump incorporated in the 40 apparatus. For example, where the city pressure within the water mains is above the pressure used in the main chamber, it is obvious that an automatically controlled valve will supply the necessary functions performed by the supply pump as previously 45 described. Fig. 6 shows a form of automatic valve that may be employed under these conditions. It comprises a diaphragm chamber 91 connected by means of the pipe 92 with the pipe 68 previously described. This diaphragm chamber is mounted above, 50 a valve 93 which is connected by means of a spindle 94 with a diaphragm mounted within the capsule 91 so that the member 55 93 moves downwardly when the pressure builds up above the diaphragm. A spring 95 may be used to return the valve to its seat 96. This valve is placed in the main water supply pipe and occupies the position 60 occupied by the pump 43 shown in Fig. 1.

It will be understood that the apparatus herein shown and described is adapted by reason of its insulation and temperating coils 21 and 22 to heat the water instead of 65 cooling it, should this process be desirable.

While this apparatus has been shown and described as particularly adapted for carbonating the water, it is obvious that it may be employed for saturating any liquid with any desired gas. It is also to be noted that 70 although the system has been described as particularly adapted for the continuous circulation of the liquid and externally of the main tank that it may be adapted for intermittent circulation of the liquid and such 75 circulation may be internally of the tank, that is to say, a pump might be mounted inside of the tank instead of externally thereof to cause the proper circulation of liquid and the proper dripping of the liquid over 80 the tempering coils in the presence of the gas.

I claim:

1. A saturator comprising a tank adapted to be partially filled with liquid and provided with a refrigerating coil, means for causing the liquid to circulate in an ascending column to a portion of the tank above normal level of the liquid therein, a gas supply connection for delivering gas into the ascending column of liquid, and means for subdividing the circulating liquid within the upper portion of the tank and exposing it in the form of a film on said refrigerating coil to the action of the gas in said portion 95 of the tank while the liquid is descending to its normal level.

2. A saturator comprising a main tank adapted to be partially filled with a liquid, a circulating means for continuously withdrawing the liquid from the lower portion of said tank, means for conducting the liquid from said circulating means to the upper portion of said tank and passing it into the upper portion of said tank in a finely divided 10 state, means for injecting a charging gas within the circulating liquid at a point between said circulating means and said tank, means adapted to supply additional liquid to said tank, and a conduit connecting said last mentioned means with said circulating means so that the fresh liquid will be intimately mixed with the circulating liquid and the injected charging gas prior to its delivery to said tank.

3. A saturator comprising a main tank adapted to be partially filled with the liquid, inclined tempering coils positioned within said main tank, heat insulating covering for said tank, circulating means adapted to continuously withdraw liquid from the lower portion of said tank and pass it upwardly into the upper portion of said tank, means positioned within said tank for subdividing the received liquid and distributing the subdivided liquid to the upper portions of the tempering coils, means for injecting a charging gas within the flowing stream of said liquid externally of said tank, means for supplying fresh liquid to said cir- 125 130

culating stream exteriorly of said tank, and means for withdrawing tempered charged liquid from the lower portion of said tank, whereby fresh liquid is first tempered and 5 treated prior to its delivery to said tank.

4. A saturator comprising a main tank having a central vertical axis encircled by a tubular helically wound tempering coil adapted to contain a refrigerating liquid, 10 means for maintaining a predetermined quantity of liquid in said tank below the upper portion of the coil, a circulating pump for withdrawing the cooled liquid from the lower portion of the tank and delivering it 15 to the upper portion thereof, a drip trough in the upper portion of the tank, adapted to receive said liquid and deliver it in subdivided form to the tempering coil, and means for delivering charging gas into the 20 ascending column of liquid circulated by the pump, whereby said liquid is partially charged with gas in said ascending column and additionally charged by exposure to free gas within the tank while distributed 25 over the surfaces of the refrigerating coil.

5. In a saturator, the combination with ducts for circulating liquid having upwardly extending portions, a pump for forcing the liquid upwardly in said ducts, a gas supply connection adapted to also deliver gas upwardly in said ducts, an auxiliary pump for adding to the liquid supply in said ducts, said auxiliary pump having its outlet connected for liquid delivery to the inlet of the 30 first mentioned pump, a motor connected for continuous operation of the first mentioned pump and having detachable connections for operating the auxiliary pump, means adapted to be actuated by the pressure of the delivered gas for connecting up the auxiliary 35 pump with said motor, and means for relieving the gas pressure and allowing the auxiliary pump to be disconnected from the motor when the liquid supply attains a predetermined volume.

6. In a saturator, the combination with a main tank, and means for maintaining a

liquid supply therein, substantially at a predetermined level, of a pump having inlet and outlet ducts connected, respectively, 50 with the lower and upper portions of said tank, a gas supply duct for delivering gas upwardly into the liquid in the pump ducts, means for distributing and delaying the liquid returned by the pump to the tank 55 during its descent within the tank to said predetermined level, and means for simultaneously refrigerating said liquid, whereby absorption of additional gas from the upper portion of the tank is promoted. 60

7. In a saturator, the combination with a main tank provided with a refrigerating coil, an annular drip pan above said coil, a duct adapted to discharge liquid into the drip pan to be distributed to the refrigerating coil, and means for injecting both gas and water into said duct. 65

8. In a saturator, the combination with a main tank provided with a refrigerating coil, a liquid distributing device in the upper portion of said tank adapted to distribute water over the surfaces of the refrigerating coil, a set of circulation pipes leading from the bottom portion of the tank to the distributing means in the upper portion thereof, an impeller pump connecting some of said circulation pipes, a mixing chamber connecting other of said pipes, and a gas injecting nozzle adapted to deliver gas upwardly in the mixing chamber. 75 80

9. In a saturator, the combination with a main tank having exterior means for withdrawing liquid from the lower portion thereof and delivering it to the upper portion, means for injecting gas into the withdrawn liquid before returning it to said tank, a refrigerator within the tank having extended heat absorbing surfaces, and means for distributing the returning liquid and gas over said heat absorbing surfaces to retard its 85 downward movement and obtain maximum exposure to the unabsorbed gases within the tank. 90

GUNTHER P. G. SCHMIDT.
